PAPER WINDING MECHANISM FOR
ACCOUNTING MACHINESRaymond A. Christian, Oakwood, Ohio, assignor
to The National Cash Register Company, Dayton, Ohio, a corporation of Maryland

Application December 18, 1951, Serial No. 262,310

3 Claims. (Cl. 242—55)

1

The present invention relates to paper-handling equipment for accounting machines and/or cash registers and is particularly directed to a rewind tally roll mechanism for such machines.

One object of the present invention is the provision of an improved paper roll rewinding mechanism for use on accounting and similar business machines.

Another object of the present invention is to provide a novel take-up device for rewinding a web of record material as it is unwound from a supply roll.

Still another object is the provision of a take-up or rewind mechanism for record material, comprising a receiving roll and a supply roll, the peripheries of which are maintained in frictional contact with a floating roller interposed therebetween, so that the operation of either roll will simultaneously operate the other roll to cause the record material to be unwound from either roll and simultaneously rewound on the other roll.

A further object of the present invention is to provide a paper feeding mechanism comprising two rolls and a web of paper, partially wound onto each of said rolls with means yieldingly maintained between the peripheries of the two rolls, whereby the operation of either of said rolls will simultaneously operate the other roll to cause the web of paper to be unwound from either of said rolls and simultaneously rewound on the other roll.

With these and incidental objects in view, the invention includes certain novel features of construction and combinations of parts, a preferred form or embodiment of which is hereinafter described with reference to the drawing which accompanies and forms a part of this specification.

In the drawing:

Fig. 1 is a side elevation, as observed from the right, of the paper roll mechanism which constitutes the subject matter of the present invention.

Fig. 2 is a top plan view of the paper roll mechanism shown in Fig. 1, said mechanism being broken away in the center and the two ends drawn together to conserve space on the drawing.

Fig. 3 is a cross-sectional view showing in detail one of the trunnion studs for supporting the supply roll of record material.

Description

The present invention is directed to a novel

10 2
rewind tally roll mechanism, indicated generally by the reference numeral 10 in Figs. 1 and 2 of the drawing, which may be readily attached to or detached from the traveling carriage of an accounting machine, said traveling carriage being indicated generally by the reference numeral 11 (Fig. 1). In this instance, the traveling carriage chosen to assist in the illustration of the present invention is of the type fully disclosed in the application for Letters Patent of the United States Serial No. 790,032 now United States Patent No. 2,626,749, issued January 27, 1953, to Raymond A. Christian et al., inventors.

15 The tally roll mechanism comprises a supply roll and a receiving roll. The web of the record material is unwound from the supply roll and then threaded around the periphery of the usual platen roll, supported by the traveling carriage 11, and then wound onto the receiving roll, which 20 has a yieldable and frictional driving connection with the supply roll. With this arrangement, rotation of the platen roll in one direction will cause the record material to be unwound from the supply roll and simultaneously rewound 25 on the receiving roll, and, conversely, rotation of the platen roll in the other direction will cause the web of the record material to be unwound from the receiving roll and simultaneously rewound on the supply roll, in case it is necessary or desirable for any reason to back-space said record material.

30 The usual traveling carriage mechanism, indicated generally by the reference numeral 11 in Fig. 1, comprises right- and left-hand supporting castings 12, only the left-hand casting being shown here, each having secured thereto overlapping angle plates 13 and 14, downwardly-bent extensions of which are bonded together with corresponding rubber blocks 15. The downward 35 extensions of the plates 13 are secured to a longitudinal escapement bar 16, having formed in its inner surface a track slot engaged by rollers 18, in turn mounted on an upward extension of a plate 19, fixed to the machine framework. The escapement bar 16 is located at the front of the traveling carriage, and the track slots therein, in cooperation with the rollers 18, assist in supporting the traveling carriage for horizontal 40 shifting movement on the machine framework. A bottom angle plate 20 (Fig. 1) and an angle bar 31, both of which extend substantially the full length of the traveling carriage and have their opposite ends secured to the right and left 45 castings 12, assist the bar 16 in maintaining said

castings 12 in rigid, spaced relationship to each other.

Secured to the bottom surface of the plate 20 (Fig. 1) is a tube 21, which extends approximately the full length of the traveling carriage and forms a rearward track, which assists the bar 16 in supporting the traveling carriage for horizontal shifting movement. The tube 21 engages V grooves formed in supporting rollers 22, only one shown here, rotatably mounted in horizontal alinement upon a bar 23, in turn secured to the machine framework. The tube 21 is maintained in accurate engagement with the grooves in the rollers 22 by a series of conical rollers 24 and 25, rotatably supported on their respective studs secured in the bar 23 and secured in horizontal posts 26, protruding from said bar 23. As previously stated, the rollers 24 and 25 coact with the tube 21 to maintain said tube in the grooves in the rollers 22 and thereby prevent vertical displacement of said traveling carriage, and said parts 21, 22, 24, and 25 also cooperate with the bar 16 and the rollers 18 to support said traveling carriage 11 for tabulating or horizontal shifting movement.

The right and left castings 12 of the traveling carriage framework rotatably support opposite ends of the central shaft of a platen roll 27, said platen used for presenting the various columns of record material wound therearound to a series of printing type carriers 8 (Fig. 1) and for feeding or line-spacing said record material in relation to said type carriers. The type carriers 8, in cooperation with an inking ribbon 9, print data relating to the various transactions upon the record material supported by the platen 27.

A front feed guide 28 is provided for guiding record material around the front of the platen roll 27, and a plurality of spring-actuated pressure rollers 29 are provided for maintaining said record material in yielding contact with the periphery of said platen roll, so that it may be fed or line-spaced by the turning of said platen roll in the usual and well-known manner. The front feed guide 28 and the pressure rolls 29 are shown herein in printing position. However, said guide 28 may be moved to a more accessible or convenient position, and the pressure rollers 29 may be simultaneously moved out of engagement with the periphery of the platen 27 to form a front feed throat to receive and guide record material around the front of said platen and into U-shaped opposed guide slots formed in two guide members 30. The guide members 30 are adjustable laterally on the traveling carriage by means of lips formed on its forward ends, which fit between the top surface of the plate 20 and the rear edge of a guide strip 33 secured to said plate 20, and by means of a clamping device 32, carried thereby, which cooperates with the angle bar 31. Therefore, the guide members 30 may be adjusted laterally to accommodate different widths of record material, and said members operate to maintain said record material in proper alinement with the printing type carriers. Any suitable means may be provided for shifting the traveling carriage horizontally from one columnar position to another, to locate the corresponding columnar divisions of the record material in relation to the type carriers 8, so that data may be recorded in said columnar divisions.

The tally roll mechanism, indicated generally by the reference numeral 10 in Figs. 1 and 2, comprises left and right side plates 34 and 35, secured to the side walls of corresponding left and right

channel members 36 and 37, in turn secured in proper spaced relationship to each other by a front plate 38 and by tie rods 39, which extend through the downwardly-bent side walls of the channel members 36 and are secured between the side members 34 and 35 by screws 40. A tie rod 41 (Figs. 1 and 2), similar to the rods 39, extends between the plates 34 and 35 and is secured in place by screws 40.

The tally roll mechanism is adjustably and removably attached to the traveling carriage 11 by means of slots in hooks 42 (Fig. 1) formed in the forward ends of the downwardly-extending side walls of the channel members 36 and 37, said slots freely engaging the outer surface of a tube 43 extending between the end castings 12, and by means of notches formed in downward extensions of the side walls of said channel members 36 and 37, the bottoms of which notches engage suitable ones of a series of equally-spaced slots cut in the top surface of a square rod 44, supported in a manner to be explained later. The notches are maintained in yielding engagement with the slots in the square rod 44 by a spring-actuated clamp 45, having upwardly-bent ears, which pivotally engage a pin 46, supported by the downwardly-extending side walls of the channel members 36 and 37, said clamp being maintained in yieldable engagement with the bottom surface of said rod 44 by a compressible spring 47, extending between the rear end of said clamp and the bottom surface of the corresponding channel member 36 or 37.

In addition to the two channel members 36 and 37, as many similar central members (not shown) as necessary may be provided to properly support the tally roll unit, depending upon the width of the record material to be used therein, which may vary from a minimum of two inches to approximately the full width of the platen 27. Each channel member 36 and 37 is provided with a stud 52, which overlies the square bar 44 and coacts with its upper surface to assist in accurately mounting the tally roll unit on the traveling carriage.

The downwardly-bent side walls of the members 36 and 37 (Fig. 1) support, at their forward ends, corresponding pins 48, which in turn rotatably support the side arms of a corresponding yoke 49, said side arms having mounted therebetween pressure rollers 50, which are maintained in yielding engagement with the periphery of the platen roll 27 by suitable compressible springs (not shown).

The plates 34 and 35 carry, respectively, bushings 53 and 54, having central bores which are in axial alinement with each other and which are freely engaged by plungers 55 and 56, having enlarged knurled heads 57 and 58 for use in moving said plungers in and out. Each plunger 55 and 56 has therein a hole arranged to receive a small ball bearing and a compressible spring, as shown in Fig. 3, for yieldingly maintaining said ball bearing in engagement with either of two annular grooves formed in the bores of said bushings 53 and 54, to yieldingly retain said plungers in either their inner or outer positions, as shown, respectively, in Figs. 2 and 3. The plungers 55 and 56 are in axial alinement with each other, and the inner ends of said plungers are arranged to freely engage opposite ends of a through bore 59 in the core portion of a supply roll of record material 60 to rotatably support said supply roll between the plates 34 and 35.

To install a new supply roll between the plates

34 and 35, the plungers 55 and 56 are pulled to their outward positions, as shown in Fig. 3, after which the supply roll is inserted between the plates 34 and 35 and the central hole 59 therein is aligned with said plungers, whereupon said plungers are pushed inwardly into engagement with the outer ends of said bore 59 to rotatably support said supply roll 60 between said plates 34 and 35. Normally, the outer edges of the outer grooves in the bushings 53 and 54, in cooperation with the ball bearings in the plungers 55 and 56, prevent removal of said plungers from their corresponding bushings. However, if it is desirable to remove either of the plungers from the bushings 53 or 54, this may be accomplished by inserting a small instrument, such as a wire or a pin, through a small hole 51 (Fig. 3) opposite the corresponding outer groove and pushing the ball bearing inwardly to a position where it will by-pass the retaining edge of said outer groove, whereupon said plunger 55 or 56 may be removed from said bushings.

Directing attention particularly to Fig. 1, the web 61 of the record material is unwound from the bottom of the supply roll 60 and is threaded between a lip 62, formed on the forward edge of the plate 36, and the downward portion of a V-shaped guide bar 63, secured between the end castings 12. The web 61 is next threaded between the periphery of the platen 27 and the pressure rollers 50; then it is guided around the forward surface of said platen, underneath the pressure rollers 29 and a series of upper pressure rollers 64. The web 61 is then guided between the downward surface of a guide bar 66 and the upper portion of the V bar 63, between upper guide extensions 67 of the plates 34 and 35, over the periphery of the supply roll 60, and thence onto a receiving roll spindle 65.

There are as many of the pressure rollers 64 as are required, depending upon the width of tally roll material, and each of said rollers 64 is rotatably supported between the side arms of a corresponding yoke member 68, in turn pivotally mounted between the side arms of a companion yoke 69, slidably mounted on a square bar 70 and retained in adjusted position on said bar by a thumb screw 71, threaded into the bail portion of said yoke 69. A spring 72, tensioned between each yoke 68 and its companion yoke 69, causes the corresponding pressure roller 64 to maintain the web 61 of the record material in frictional contact with the periphery of the platen 27, so that rotation of said platen will feed said record material.

When the front feed throat mechanism, comprising the guide 28 (Fig. 1), is in closed position, as shown here, the corresponding pressure rollers 29 are maintained in yielding contact with the periphery of the platen 27 and at this time assist in maintaining the record material web 61 in frictional engagement therewith. However, this is incidental, as the pressure rollers 50 and 64 maintain sufficient frictional contact between the web 61 and the periphery of the platen, so that said web 61 may be fed regardless of the open or closed throat condition of the guide 28 and the pressure rollers 29.

Opposite ends of the square bar 70 and the channel bar 66 (Fig. 1) are supported between 70 similar side plates 73 (only the left plate shown here), in turn rotatably supported by axially-aligned trunnion studs 74, carried by the right and left castings 12. Each of the plates 73 is operatively connected to a companion slide 77 by tog-

gle links 75 and 76, said slides 77 being shiftably supported on their corresponding casting 12. The right- and left-hand slides 77 have, rigidly connected thereto, opposite ends of the bar 44 to support said bar for sliding movement in unison therewith.

Manipulation of the toggle links 75 and 76, by means of a convenient finger piece 78 formed on each of said links 76, rocks the plates 73 clockwise (Fig. 1) and simultaneously shifts the bar 44 rearwardly, to rock the upper pressure rollers 64 also clockwise out of engagement with the periphery of the platen 27 and to shift the entire supply roll assembly rearwardly to move the pressure rollers 50 out of engagement with the periphery of said platen 27, so that the web 61 of the record material may be conveniently removed from or threaded around said platen roll. The side plates 34 and 35 (Figs. 1 and 2) are provided, respectively, with inwardly-bent extensions 79 and 80, which underlie the upper portion of the web 61 of the record material to support said web in case excess slackness should occur therein, and thus insure that said web does not become entangled in protruding portions of the carriage mechanism.

Each end of the receiving roll spindle 65 (Figs. 1 and 2) has formed thereon a knurled knob 83, for use in manually turning said spindle to start the paper web 61 winding thereon, and for use in removing said spindle from the tally roll assembly when desirable or necessary. Adjacent each of the knobs 83, the spindle 65 has an undercut bearing portion 81, engaged by open slots 84 in the hook-shaped upper ends of companion supporting arms 85, each carrying a hub in its lower end which freely engages an axle 86, supported by the plates 34 and 35. For convenience in handling the tally receiving roll, the knobs 83 are arranged to extend outwardly beyond the plates 34 and 35 (Fig. 2), said plates each being provided with a curved surface 82 (Fig. 1), which is concentric with the center of the axle 86, said surface being adjacent to and providing clearance for the undercut portions 81, so that the spindle 65 may rock freely back and forth with the arms 85. Each of the arms 85 carries a stud 87, which extends inwardly through a slot 88 in the corresponding plates 34 and 35, said slots being concentric with the center of the axle 86. Springs 89, connected between the studs 87 and fixed studs in the plates 34 and 35, urge the arms 85 counter-clockwise, as viewed here, to normally maintain the periphery of the receiving roll 65 in yielding contact with a series of rubber driving rollers 90 molded around central bushings which rotate freely on a rod 91, opposite ends of which are supported in the upper ends of companion arms 93, pivoted at their lower ends on the axle 86. Spacing sleeves 92, free on the rod 91, are provided for proper spacing of the driving rollers 90 from the corresponding arms 93 and for spacing said rollers in proper relationship to each other on said rod 91. Each end of the receiving spindle 65 is provided with a series of closely-spaced serrations 94 for gripping the record material, to prevent it from slipping, when said spindle 65 is revolved to start said record material winding therearound. The open slots 84 in the arms 85 permit the spindle 65 to be readily removed from said arms for convenience in starting the web of the record material winding therearound, after which said spindle may be inserted in the slots 84, whereupon the springs 89 become effective to maintain said record material in

yielding contact with the rollers 90 and to simultaneously maintain said rollers in frictional engagement with the periphery of the supply roll 60, as shown in Fig. 1.

After the web 61 of the record material has been properly threaded around the platen, as shown in Fig. 1, clockwise rotation of said platen will cause said web 61 to be pulled or unwound from the supply roll 60 and rotate said supply roll clockwise. Clockwise rotation of the supply roll 60, through the rollers 90, will simultaneously drive the receiving roll spindle 65 also clockwise to cause the web 61 of the record material to be rewound therearound as it is unwound from said supply roll. By referring to Fig. 1 it will be noted that the center of the receiving roll spindle 65, the center of the rod 91, and the center of the plungers 55 and 56 are on a common radius in relation to the center of the axle 86, and it is therefore obvious that the operating relationship between the supply roll 60, the friction rollers 90, and the receiving roll 65 is always the same regardless of the diameter of said supply roll and said receiving roll.

If for any reason it is desirable to back up or reverse the feed of the web 61 of the record material, an example of which would be the checking of a previous entry, reverse or counter-clockwise rotation of the platen roll 27 causes said web 61 to be pulled or unwound from the receiving roll 65 and simultaneously rewound on the supply roll 60, as the parts of the tally roll mechanism are arranged to operate in either direction with equal facility.

Any time it is desirable to separate the portion of the record material 61, rewound on the spindle 65, from the other portion of said record material, all that is required is to sever the web 61, near said spindle 65, and remove said spindle from the slots in the arms 85. After this, the spindle 65 may be slipped out of the portion of the record material 61 rewound thereon, and the web 61 may be again started around said spindle 65.

Some business systems require that a statement slip be inserted in the front feed throat in front of the web 61 of the record material, and under such conditions it is necessary that some form of duplicating medium be interposed between said statement slip and said record material, so that a duplicate of the entries made upon said statement slip will simultaneously be made upon said web of the record material. In some cases, this duplication of records is accomplished by means of an inking ribbon inserted between the statement slip and the web of the record material, and in other cases it is accomplished by means of a web of carbon paper, which is the exact width of the web 61 of the tally roll and overlies said web and is simultaneously unwound and rewound in unison therewith.

The tally roll mechanism may be made in various sizes to accommodate different widths of record material, which, as stated before, may vary from a minimum of about two inches to approximately the full width of the platen roll 27. In certain applications—for example, where a narrow tally roll is required—it has been found that the pressure rollers 58 (Fig. 1) and their supporting yokes 49 may be omitted without in any way interfering with or impairing the proper operation of the tally roll mechanism. In such cases, the upper pressure rollers 64 have proved to be entirely adequate in providing the proper feeding tension between the web 61 of the tally roll and the periphery of the platen 27.

Stop studs 95 (Fig. 1), extending inwardly from the plates 34 and 35, cooperate with the corresponding arms 93 to limit the counter-clockwise movement of said arms and to hold the rollers 90 away from the plungers 55 and 56 and other protruding parts of the tally roll mechanism, when the supply roll 60 is removed from said tally roll mechanism.

While the form of mechanism shown and described herein is admirably adapted to fulfill the objects primarily stated, it is to be understood that it is not intended to confine the invention to the one form or embodiment disclosed herein, for it is susceptible of embodiment in various other forms.

What is claimed is:

1. In an accounting machine having a traveling carriage constructed and arranged to support a platen roll for feeding or line-spacing record material wound therearound, the combination of a framework removably mounted on the traveling carriage; a supply roll of record material mounted for rotation in the framework, the web of said record material adapted to be threaded around the periphery of the platen so that rotation of said platen will unwind said web from said supply roll; a receiving roll for rewinding the web of the record material as it is unwound from the supply roll; an axle mounted in the framework; arms pivoted on the axle and constructed and arranged to removably support the receiving roll for rotary and rocking movement, said rocking movement being in substantial radial alignment with the center of the supply roll; friction rollers; arms pivoted on the axle and constructed and arranged to rotatably support the friction rollers between the supply and receiving rolls and in substantial radial alignment with the center of said supply and receiving rolls; and yieldable means coacting with the arms for supporting the supply roll to maintain the periphery of said supply roll in yielding contact with the periphery of the friction rolls, and to maintain the periphery of said friction rolls in yielding contact with the periphery of the supply roll, so that rotation of said supply roll, when the web of the record material is unwound therefrom, will simultaneously rotate the receiving roll to rewind said web thereon.

2. An accounting machine having means to print records on record material and having a traveling carriage supporting a platen roll for presenting said record material to the printing means and for feeding or line-spacing said record material in relation to said printing means, the combination of a framework removably mounted on the traveling carriage; a first record material roll rotatably mounted on a fixed axis in the framework; a second record material roll rotatably mounted on an axis supported in the framework so as to rock on a radius which coincides with the axis of the first record material roll, both of said record material rolls having wound therearound portions of a continuous web of record material, the part of said web between said record material rolls being wound around the platen roll for presentation to the printing means and for line-spacing or feeding by said platen roll; friction rollers rotatably mounted on an axis rockably supported in the framework on the same radius as the second roll, said friction rollers positioned between the peripheries of the two record material rolls; and yieldable means coacting with the second record material roll to squeeze the friction rollers between the peripheries of the two record material rolls so that rotation of the platen

roll in one direction will cause the web of the record material to be unwound from the first record material roll and simultaneously rewound onto the second record material roll, and rotation of said platen roll in the other direction will cause the web of the record material to be unwound from the second record material roll and simultaneously rewound onto the first record material roll.

3. In an accounting machine having means to print records on record material and having a traveling carriage supporting a platen roll for presenting said record material to the printing means and for feeding or line-spacing said record material in relation to said printing means, the combination of a framework removably mounted on the traveling carriage; a record material supply roll removably supported on a fixed axis in the framework; an axle mounted in the framework parallel to the axis of the supply roll; a pair of arms rotatably mounted on the axle, said arms having open slots near their upper ends; a record material receiving roll spindle removably supported in the slots in the arms and rockable by said arms on a radius which passes through the approximate center of the axis of the supply roll, the web of said record material arranged to be unwound from the supply roll, thence around the platen roll, for presentation to the printing means, and for feeding by said platen roll, said web being finally rewound on the spindle to form a receiving

roll; pressure rollers mounted in the removable framework and constructed and arranged to yieldingly press the web of the record material against the platen roll to insure proper and accurate feeding of said record material; a second pair of arms rotatably supported on the axle; a rod supported by the second pair of arms on the same radius as the spindle; a plurality of yieldable friction rollers mounted for independent rotation on the rod, said friction rollers interposed between the peripheries of the supply and receiving rolls; and springs connected between the first pair of arms and the framework, and acting to yieldingly squeeze the friction rolls between the peripheries of the supply and receiving rolls, whereby rotation of the platen roll unwinds the record material from the supply roll and simultaneously rewinds said record material on the receiving roll spindle.
